(57) **CLAIM**

We claim the ornamental design for a vehicle rear lighting unit, as shown and described.

DESCRIPTION

FIG. 1 is a rear perspective view of a vehicle rear lighting unit;

FIG. 2 is a left side view thereof;

FIG. 3 is a right side view thereof;

FIG. 4 is a rear view thereof;

FIG. 5 is a front view thereof;

FIG. 6 is a top view thereof;

FIG. 7 is a bottom view thereof; and,

FIG. 8 is a perspective view of the vehicle rear lighting unit on a vehicle.

The broken lines are included for the purpose of showing environment and portions of the vehicle rear lighting unit that form no part of the claimed design.
